Attorney.

UNITED STATES PATENT OFFICE

VICTOR L. STOLZE, OF WAUSAU, WISCONSIN

RIBBON-GOLD MAGAZINE

Application filed March 20, 1929. Serial No. 348,625.

The present invention relates to devices for holding ribbon gold, ribbon silver, or the like, and aims to provide a novel and improved ribbon gold magazine wherein strips or ribbons of gold or other material are conveniently supplied for application to gilding rolls or type, and the like, for use in gilding books or the like.

Another object of the invention is the provision of a novel and improved magazine for supplying strips or ribbons of gold or other material in a convenient manner, and to save the time and waste incident to cutting strips from sheets of gold leaf as has been the custom heretofore.

A further object is the provision of a ribbon gold magazine having novel means for mounting and actuating ribbons carrying the strips of gold leaf or other material, the ribbons and strips being of different widths for type or gilding rolls of different widths.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a plan view of the device.

Fig. 2 is a section on the line 2—2 of Fig. 1.

Fig. 3 is a fragmentary elevation illustrating one of the winding spools.

Fig. 4 is an enlarged elevation of one of the clutch disks, portions being shown in section.

Fig. 5 is a fragmentary elevation illustrating two of the rolls of ribbon.

The device comprises a frame 7 constructed of wood, metal or other suitable material, and having the side members 8 and a top pad 9 over which the ribbons 10 carrying the gold leaf or other material pass. Said pad is preferably provided with shallow channels or depressions in which the ribbons move, and the ribbons are of different widths.

Said ribbons are supplied in rolls 11 and 50 have the gold leaf or other material thereon

to be exposed over the pad 9 when the ribbons are unwound from the rolls, so that the gold leaf or other material may be picked up by a gilding roll, type, or the like, for applying letters, borders, or the like, to books and other objects.

The rolls 11 are supported beyond one edge of the pad 9 within U-shaped spring clips 12 which have their intermediate portions secured to the frame 7, and said rolls are held 60 frictionally between the arms of the clips to prevent the rolls from turning unless the ribbons are pulled therefrom.

A rod 13 extends through apertures in the clips 12 and through the rolls 11 to support said rolls for rotation. The rod 13 may be withdrawn to permit new rolls to be inserted in the clips 12, and the arms of the clips being sprung toward one another will hold the rolls between them after the rod 13 is 70 withdrawn and before it is inserted.

The ribbons 10, after passing over the pad or top 9, are wound on spools or reels 14 which are mounted for rotation on a shaft 15 beyond the edge of the pad 9 opposite to the rolls 11. The shaft 15 is mounted for rotation in bearings 16 secured on the side members 8 of the frame, and said shaft has a knob 17 at one end for conveniently rotating the shaft by hand.

A spring pressed ball 18 is mounted in one bearing 16 to engage in an annular groove 19 in the shaft 15, for holding the shaft in position, but permitting the shaft to be withdrawn from the bearings and spools to permit the spools to be removed for taking the ribbon therefrom and replacing the spools as they become filled.

Clutch disks 20 are mounted on the shaft 15 between the pairs of spools, and have keys 90 or feathers 21 slidable in a groove 22 in the shaft 15 so that said clutch disks rotate with the shaft. The sides of the spools adjacent to the clutch disks have pins 23 between which the keys 21 are engageable when the disks 20 are shifted longitudinally on the shaft 15.

Each disk 20 has a spring-pressed ball 24 therein engageable in an annular groove 25 in the shaft 15 for holding the disk in its intermediate or neutral position with the key 100

21 disengaged from the corresponding pins 23, but the disk may be forced in either direction to make a clutch connection with the corresponding spool 14.

5. U-shaped spring clips 26 are secured at their intermediate portions to the frame 7 and have their arms disposed astride the spools 14, so that when the shaft 15 is withdrawn, the clips 26 will frictionally hold the 10 spools, and they may be readily removed and replaced for removing the ribbon therefrom.

This will prevent the spools 14 from dropping when the shaft 15 is removed, and the spools are also supported in position by the 15 clips so that the shaft may be readily inserted.

In use, any selected ribbon 10 may be advanced over the cushion 9 by shifting the corresponding clutch disk 20 to engage its key 20 21 with the pins 23 of the spool 14 on which said ribbon is wound. Then, by turning the knob 17 the ribbon is wound on said spool and the gold leaf or other material is brought over the pad to be removed by the gilding 25 roll, type, or the like. In the same manner, other ribbons may be advanced, and a convenient selection of different widths of gold leaf strips are available.

Having thus described the invention, what 30 is claimed as new is:

1. A device of the character described comprising a frame having a pad, spring clips on the frame for frictionally supporting rolls of ribbons beyond one edge of the pad, and 35 spools for winding up the ribbons mounted on the frame beyond the opposite edge of the pad.

2. A device of the character described comprising a frame having a pad, spring 40 clips on the frame for frictionally holding rolls of ribbons therein beyond one edge of the pad, a rod inserted in said clips for supporting said rolls for rotation, and spools for winding up the ribbons mounted on the frame beyond the opposite edge of the pad.

3. A device of the character described comprising a frame having a pad, means for supplying ribbons to pass over the pad, spools for winding up said ribbons after passing 50 over the pad and located below the plane of the pad, a shaft mounted on the frame and on which said spools are rotatable, and clutch members mounted on the shaft and engageable with said spools.

4. A device of the character described comprising a frame having a pad, means offset 55 downwardly from the plane of the pad for holding rolls of ribbons beyond one edge of the pad, a shaft mounted on the frame beyond the other edge of the pad and removable longitudinally from the frame, spools below the 60 plane of the pad rotatably mounted on the shaft for winding up said ribbons, and clutch members mounted on the shaft to engage said 65 spools.

5. A device of the character described comprising a frame having a pad, means for holding rolls of ribbons beyond one edge of the pad, a shaft mounted on the frame beyond the other edge of the pad and removable longitudinally from the frame, spools rotatably 70 mounted on the shaft for winding up said ribbons, clutch members mounted on the shaft to engage said spools, and spring clips carried by the frame and engaging said spools to support them when said shaft is withdrawn 75 from the frame.

6. A device of the character described comprising a frame having a pad, means supported from the frame and located beyond one edge of the pad for mounting rolls of ribbons and including a removable rod on which the rolls may be mounted for rotation, said means having spring elements to frictionally engage said rolls for supporting them when 80 said rod is withdrawn, and spools for winding up the ribbons mounted on the frame beyond the opposite edge of the pad.

7. A device of the character described comprising a frame having a pad, means for supplying ribbons to pass over the pad, spools for winding up said ribbons after passing over the pad, and means for mounting said spools from the frame including a removable shaft on which said spools are rotatable, the 85 last named means including spring elements to frictionally engage the spools and support them when said shaft is withdrawn.

In testimony whereof I hereunto affix my signature.

VICTOR L. STOLZE.
